UNITED STATES PATENT OFFICE.

CARL BREER, OF DETROIT, MICHIGAN, ASSIGNOR TO CHRYSLER CORPORATION, OF HIGHLAND PARK, MICHIGAN, A CORPORATION OF DELAWARE.

METHOD OF MAKING PISTON PINS.

Original application filed September 28, 1925, Serial No. 58,982. Divided and this application filed May 29, 1926. Serial No. 112,601.

This application is a division of my application Serial No. 58,982, filed September 28, 1925.

This invention relates to piston pins and 5 more particularly to the method of making the same.

In the construction of aluminum pistons, considerable difficulty has been experienced in fitting the piston pins into the piston 10 bosses because of the difference in the coefficient of expansion of the aluminum piston and bosses over that of the steel pin. If the pin is fitted closely in the bosses, there is a tendency to bind under extreme 15 cold conditions because of the relatively large contraction of the aluminum with respect to the steel. If the pin is fitted in loosely, there is a tendency to knock under extreme heat conditions due to the relatively 20 large expansion of the aluminum with respect to the steel.

It is the primary object of my invention to provide a method of making a piston pin construction which will tend to cause the pin 25 to have substantially the same co-efficient of expansion as the piston and bosses.

With the above and other objects in view, my invention consists in the method and process of making the same, as set forth in 30 the specification, claimed in my claims and shown in the accompanying drawings, in which:

Fig. 1 is a longitudinal sectional view of 35 a piston pin constructed in accordance with my invention.

Fig. 2 is a longitudinal sectional view illustrating the method of making the same.

Fig. 3 is a sectional view of a piston showing my improved pin mounted therein.

Fig. 4 is a longitudinal sectional view 40 showing a modified method of making the pin.

I have shown a tubular steel shell 5 having a core 6 of aluminum held therein by 45 the end flanges 14. This composite pin is fitted into the bosses 7 of an aluminum piston 8.

For the manufacture of my improved pin 50 the core 6 is inserted in the shell and is of sufficient length to extend a few thousandths of an inch beyond the ends of the shell. The shell and core are then placed in a die consisting of the members 9 and 10, the opening in the die being slightly larger than the

circumference of the shell as illustrated at 55 11. A stationary member 12 is brought to bear against one end of the core 6 and a movable heading punch 13 is positioned opposite the other end of the core. The heading punch 13 is then moved to strike that 60 end of the core which is opposite so as to upset the core in the shell 5, with the result that the core is compressed within the shell and the shell will be forced outwardly a relatively small amount as indicated by the clearance 11, so as to place it under an expansive strain. In some cases this operation may result in the circumference of the shell being slightly out of round 65 in which event it may be milled to a perfectly round formation and then placed in the bosses 7 of the piston 8. The end flanges 70 14 may be formed in this operation to definitely locate the core in the shell under all 75 temperature conditions.

It will be apparent that a piston pin constructed in accordance with the above description will be highly responsive in expansion and contraction to heat and cold. When subjected to heat the aluminum core 80 will follow its natural tendency to expand the steel shell a greater amount than the shell would normally expand under the same heat. Likewise when subjected to colder temperatures, the core 6 will contract and because of 85 the fact that the shell 5 has been placed under an expansive strain the shell will follow the contraction of the core. The obvious result will be that the pin and piston will expand and contract in substantially the same ratio. 90 The clearance 11 permits slight expansion of the shell, when being placed under expansive strain, without endangering splitting of the shell.

It will be obvious that other combinations 95 of material than steel and aluminum may be utilized in my invention, and I do not wish to be limited to this combination.

As a modification in the manufacture of my improved pin, I have shown in Fig. 4 the 100 pin being disposed in a die, as in Fig. 2. The core, however, is of slightly less length than the shell and the members 12 and 13 meet the ends of the core within the shell. In this method, the upsetting of the core must 105 result in expansion of the shell, inasmuch as there is no other escape for the material of the core.

Various other changes may be made in the arrangement, combination and construction of the various parts, without effecting the process used in the manufacture thereof or without departing from the spirit of my invention, and it is my intention to cover by my claims such changes as may be reasonably included within the scope thereof.

What I claim is:

14. 1. The process of making an article of manufacture which consists in compressing in a tubular member a core having a higher coefficient of expansion than the tubular member.
15. 2. A process as described in claim 1 wherein said core is compressed to an extent as to place said tubular member under an expansive strain.
16. 3. The process of making an article of manufacture which consists in placing a core in a tubular member and then upsetting the core to compress it in the tubular member.
17. 4. The process of making an article of

manufacture which consists in placing in a tubular member a core having a higher coefficient of expansion than the tubular member and then upsetting the core to place the tubular member under an expansive strain.

18. 5. The process of making an article of manufacture which consists in placing a core in a tubular member, holding the tubular member in a member design to permit only slight expansion thereof, and then upsetting the core to compress it in the tubular member and place the tubular member under expansive strain.

19. 6. A process as set forth in claim 5 wherein said tubular members is then trimmed to a true outside round formation.

20. 7. The process of making an article of manufacture which consists in placing an aluminum core in a steel shell, then upsetting the core to compress it in the shell and place the shell under an expansive strain.

CARL BREER.
